Application October 11, 1945, Serial No. 621,665

6 Claims. (Cl. 236—79)

(Granted under the act of March 3, 1883, as
amended April 30, 1928; 370 O. G. 757)

1

This invention relates to a manifold-pressure type automatic metering control and especially to a device for automatically controlling the rate of fuel flow to an internal combustion engine.

The present device is designed to automatically actuate the capacity control of the fuel-injection pump, which in turn delivers fuel through injection lines and nozzles to each of the individual engine cylinders or intake pipes in accordance with the mass rate of air flow to them. The engine for which the proposed control is used is one in which the charge is ignited by an electric spark and in which the charge must have definite fuel-air proportions.

The purpose of this invention is to maintain predetermined proportions of fuel flow to air flow into the engine, independent of the altitude and power at which the engine is run, taking into account the volumatic efficiencies of the engine and of the fuel injection pump; thus providing for fuel-air mixture control at any engine speed and air flow.

The existing fuel injection systems that use a venturi for measuring the air flow and proportioning the fuel delivery to an engine encounter difficulties and disadvantages in that the venturi imposes a restriction in the intake air line that results in a loss of critical altitude of the aircraft engine, and the venturi cannot proportion the fuel delivery with the desired accuracy, for if it were made small enough to proportion satisfactorily at low air flows, it would impose too great a restriction at high air flows, requiring that a compromise design must necessarily be selected with the result that greater metering tolerances must be permitted than are desirable.

Various existing fuel injection systems other than a venturi have been used for measuring air flow and proportioning fuel flow to an engine, but none of these have been entirely satisfactory.

An object of this system is to provide for rich and lean operation in cruising, for enrichment under high power take-off conditions and for adjustable mixture ratios in the idling range.

Another object is to provide a system which will account for engine air flow under all conditions of engine operation, and thus maintain constant fuel-air ratios under varied engine operating conditions.

By providing for varied mixture ratios, the

2

metering system protects the engine against over-heating, misfiring, backfiring, etc., under all conditions of engine operation and, in addition, permits economical operation in the cruise range which is necessary with long-range aircraft.

The features of this invention are described in connection with the accompanying drawings.

Figure 1 shows the required operating conditions that a system must provide;

Figure 2 is an obliquely sectioned view of the mechanism;

Figure 3 is a sectioned view of the idling adjustment;

Figure 4 shows the joint between the directing lever and the piston shaft;

Figure 5 shows the joint between the pilot lever and the flexible rod;

Figures 6, 7, and 8 are views of the hinge joint;

Figure 9 shows the pin used with the hinge joint;

Figure 10 is a detailed sketch of the bellows device, showing its connection to an engine;

Figure 11 is a sketch of a bellows device with a bi-metallic temperature compensation element;

Figure 12 is a sketch of a bellows device with a hydraulic capsule temperature compensation element;

Figure 13 is a kinematic diagram of the servo-lever system;

Figure 14 is a right-angle projection of Figure 13; and

Figures 15 and 16 show a variation of the servo-lever system.

In Figure 1, abscissa A represents air flow to the engine in pounds per hour and ordinate B represents fuel-air ratio. Distance C—D along abscissa A represents the air flows under idling conditions, D—E under cruising conditions, E—F under higher power conditions, and F—G under take-off conditions. Curve H represents the air flows and fuel-air ratios required with operation of the metering control in the "automatic rich" setting, whereas curve I represents the conditions for the "automatic lean" setting. Curves J and K represent the range of fuel-air ratios that the idling adjustment must provide. None of the existing fuel-injection systems that operate without a Venturi system are capable of providing the mixture ratios shown.

The air consumption of an engine can be rep-

resented as a continuous single-valued function of the absolute intake-manifold pressure, absolute exhaust back pressure, absolute intake-manifold temperature, and engine speed. Mathematically, the relation can be stated as follows:

$$\text{Air flow/cycle} = f_1(P_m) + f_2(P_e) + f_3(T_m) + f_4(N)$$

where

P_m , absolute intake-manifold pressure

P_e , absolute exhaust back pressure

T_m , absolute intake-manifold temperature

N , engine speed

This equation takes into account the air flowing to the engine under all conditions of engine operation; that is, power, speed, and altitude. The relation between these variables is experimentally determined by operating the engine under varied operating conditions. The equation so determined can then be applied to all engines of a given design.

In the subject control system, pressure- and temperature-sensitive units are combined to produce a displacement that is proportional to the absolute intake-manifold pressure, the absolute exhaust back pressure, and the intake-manifold temperature in accordance with the preceding experimentally determined relation of these variables to engine air flow. By means of a hydraulic servosystem, this displacement is magnified and caused to actuate the capacity-control lever of the fuel-injection pump. The design of the hydraulic servosystem is such that a change in magnification of movement is possible, the system being similar to a simple lever system with a movable fulcrum. Once a multiplying ratio is selected, this ratio will be maintained for all air flows. This method of control enables the system to maintain two definite fuel-air ratios, rich and lean, in the cruise range. Mixture enrichment for increased power and take-off operation is provided by interposing a cam between the servopiston shaft and the capacity-control lever of the fuel-injection pump. This cam also permits introduction of a multiplying factor in the linkage system and therefore provides for adaptability of the control to any engine. Idling adjustment is provided for by changing the displacement response, at low air-flow values, of the pressure- and temperature-sensitive device by an adjustable means. The mechanical features are described in detail in succeeding paragraphs.

In Figure 2, a metal case 1 houses the various parts of the mechanism. Bellows devices 2 and 36, which are anchored to case 1 by means of screws 3, measure engine air flow and actuate shaft 4. Shaft 4 is connected with tubular directing lever 5 by spherical trunnion 6 inserted through a slot (not shown) similar to slot 7. Trunnion 6 causes lever 5 to follow movements of shaft 4 with no restraint, rotatively or axially, of said lever by said shaft. Lever 5, being thus acted upon and being subjected to considerable restraint at bearing 8 due to resistance on piston shaft 9 of entrapped oil in cylinder 10 acting on piston 11, is caused to move in the direction of action of shaft 4, pivoting about trunnion 8 and causing a corresponding motion of the end of pilot lever 12. Lever 12 is connected to lever 5 by means of special spherical bearing 13, said bearing being slidably and rotatively mounted on both levers 12 and 5 so as to eliminate binding or undesirable restraint of said levers. Lever 12, being caused to move as described and having as its fulcrum pivot bearings 14, reverses and transmits to pilot valve 16 the motion imparted to it

at its connection with lever 5. This motion is transmitted to pilot valve 16 through flexible rod 17 which accommodates alignment differences between bearing 15 and the extended line 5 of motion of pilot valve 16. Pilot valve 16 being thus displaced by action of bellows device 2 on the lever system just described admits oil under pressure from channel 18 to channel 19 or 20, simultaneously connecting those channels not 10 connected to said high-pressure channel 18 to low pressure channel 21 or 22. This action results in a pressure difference on opposite sides of piston 11 causing it to move in the direction of lowest pressure. Fulcrum pivot bearings 14 are mounted on stub 50 attached to plate 51. Plate 51 is rotatable about the collar 52 secured to the metal case 1 axially with the valve 16. Lever 53 connected to a handle not here illustrated turns shaft 54 having crank 55 engaged 15 by pin 56 fixed in plate 51, and adjustment of the lever 53 imposes a change in the positioning of fulcrum 14 with respect to the point of connection to the directing lever 5, this acting to vary the distance of bearing 13 from the trunnions 6 and 8 and to therefore vary the resultant motion of the piston 11 and the dependent fuel flow.

Piston 11, being thus caused to move by the action (through the described lever system) of bellows device 2 on pilot valve 16, is arrested in its motion by the restoration through said lever system of pilot valve 16 to a position where lands 23 and 24 block the passage of oil into or out of channels 19 and 20. Pilot valve 16 is now in 30 equilibrium and will maintain this neutral position indefinitely, holding piston 11 stationary until pilot valve 16 is moved by action of bellows devices 2 and 36 on the lever system as described, or by other means. Movement of bellows 2 thus 35 produces definite predictable amounts of motion of piston shaft 9 by moving shaft 4. The magnitude of these motions is proportional in a constant ratio dependent on the distances of bearing 13 from trunnions 6 and 8, respectively. A detailed discussion of the means of attaining this proportional relationship is given in succeeding paragraphs.

The controlled movement of piston 11 actuates cam plate 26, through piston shaft 9, and ball bearing 25 which is fitted in slot 26a. Cam plate 26 is mounted on ball bearing 27 fixed in case 1 so that the sliding action of piston shaft 9 causes cam plate 26 to rotate about bearing 27. Power-delivery shaft 30, which is mounted in 50 case 1 and connected to quantity-control lever 33 of engine fuel-supply device 38 through link 32, is actuated by cam surfaces 28 to which ball bearing 29 is fitted. Ball bearing 29 is also attached to shaft 30. The position and curvature of cam surfaces 28 can be varied in their manufacture to attain an infinite range of motion relationships between power-delivery shaft 30 and piston shaft 9. By this means the fuel-metering characteristics of fuel-supply device 38 and the air-flow-rate measuring characteristics of bellows devices 55 2 and 36 can be matched to attain constant ratios of fuel and air or such increased or decreased ratios of fuel and air as may be required in practical engine operation.

50 Bellows devices 2 and 36, shown in detail in Figure 10, are diagrammed to illustrate their connection to an engine. Air is pumped to engine cylinder 39 by supercharger 40 through inlet pipe 40a, and the products of combustion are 55 discharged through exhaust pipe 41. Pitot tubes

34a and **35a** are arranged to circulate air from inlet pipe **40a** through inlets **34** and **35** and through the bellows compartment in case **1**, and to maintain in said chamber at all times the same absolute pressure as exists in inlet pipe **40a**. Bellows unit **2** consists of flexible bellows **2a** mounted on chamber **2c** which in turn is fastened to bellows **36**. The other end of bellows **36** is fastened to rigid strut **1a**. Shaft **4** is so attached to the free end of bellows **2** so that as the pressure is increased in the bellows compartment both bellows move to the right against springs **2b** and **36a** or, as the pressure in the bellows compartment is reduced, conversely move to the left.

Bellows **2** is sealed and filled with an inert gas, the pressure of which increases, causing the bellows to expand, when the temperature in case **1** is increased in accordance with the temperature of air circulated to it from engine inlet pipe **40a**. The magnitude of response to changes in inlet-air temperature is determined by the pressure and temperature of the gas charge of bellows **2** at the time of sealing. Chamber **2c** provides additional volume for this gas and reduces the volume change error due to the expansion and contraction of bellows **2** to an insignificant amount. Strut **1a** eliminates the error due to the thermal expansions of case **1** and bellows **2** and **36**, thus making the assembly responsive solely to the temperature of the gas in the gas-filled bellows **2**.

Bellows **36** is so arranged that its internal pressure follows the exhaust back pressure by means of communicating line **37**. By this arrangement, exhaust back pressure affects the movement of bellows **36** in a manner opposite to the inlet-pipe pressure, corresponding to the opposite effects of exhaust back pressure and inlet-pipe pressure on air quantity flowing through the engine. The relative magnitudes of these effects on the movement of the free end of the bellows assembly are determined by the relative sizes of bellows **2** and **36** and springs **2b** and **36a**. It is seen then that the relative influence of inlet-air pressure, inlet-air temperature, and exhaust back pressure on the magnitude and direction of motion of the free end of the bellows assembly can be predetermined. This predetermination makes possible the construction of a bellows unit that produces a mechanical movement in accordance with changes in air flow as defined by the experimentally determined mathematical relationship between the parameters (inlet-air pressure, inlet-air temperature, and exhaust back pressure) given previously.

Several alternate arrangements for causing the bellows unit to move in response to temperature changes have been considered. One method consists of the application of a bimetallic device in the space occupied by the volume chamber **2c**. Figure 11 shows bimetallic device **2d** attached between bellows **2** and **36**. An increase in temperature causes bimetallic device **2d** to increase its length along the axis of bellows **2** and **36** by the well-known principle of warpage of joined metals of unequal temperature-expansion rates. Another method of obtaining a mechanical movement of the bellows unit through a change in the air temperature of the engine inlet is to provide a hydraulic-capsule unit between the bellows units shown in Figure 12. Capsule **2e**, of small volume, is connected by capillary tube **2f** to a bulb **2g**, of relatively large volume, placed in the engine inlet pipe **40a**. This system is charged with a volatile liquid that produces an increase

in pressure within capsule **2e** when the temperature of the bulb **2g** is increased. Capsule **2e** expands because of the increased internal pressure and produces a movement along the axis of the bellows assembly in accordance with the temperature of bulb **2g**, which is immersed in the engine inlet air.

Bimetallic device **2d** or hydraulic-capsule unit **2e** can be arranged in any position that causes the proper direction and magnitude of motion of bellows shaft **4** to result in correct temperature response.

Figure 3 shows an accessory to the apparatus described above that is effective only when the engine is idling and that causes the control to enrichen the fuel-air mixture during this period. Bellows devices **2** and **36** elongate at low rates of air flow (Fig. 2), as explained above, and move bellows shaft **4** upward, so piloting the servo-mechanism that the fuel supply is thereby reduced. The rate of elongation of the bellows due to lower rates of air flow is decreased by causing spring **4d** in the idling device of Figure 3 to act against the elongating bellows. This action is accomplished by providing lug **4a** (Figs. 2 and 3) extending from bellows shaft **4**. Lug **4a** comes in contact with pin **4f** as lug **4a** moves upward; sleeve **4e** is moved upward also, for it is connected to pin **4f** by screw threads. Sleeve **4e** has an extension shoulder that carries spring **4d** and that, being restrained by extension **4b** of case **1**, is thus compressed by the upward movement of the assembly of sleeve **4e** and pin **4f**. Spring **4d** thus acts against the expanding action of bellows **2**, reducing its rate of expansion as the engine air-flow rate diminishes in the idling range and enriching the fuel-air ratio.

The initial tension of spring **4d** is controlled by threaded ring **4g**. If this initial tension exceeds zero, the upward motion of bellows **2** and **36** is arrested until a certain decrease of air flow occurs. The rate of fuel delivery to the engine remains constant during the range of this air-flow decrease, causing an abrupt enrichening of the mixture. By adjusting threaded ring **4g**, the magnitude of this range may be regulated to desirable amounts.

The range of travel of spring **4d** is limited by threaded ring **4c**, the position of which is adjustable with respect to bellows-actuated sleeve **4e**. Such adjustable limitation of the bellows travel is desirable to fix the minimum rate of fuel flow to the engine.

The rate of air flow at which the idling device described above commences to act is adjusted by screwing threaded pin **4f** into or out of sleeve **4e**, thus affecting the amount of movement of bellows-actuated lug **4a** before contact with pin **4f** occurs.

Figure 4 shows details of the joint between directing lever **5** and piston shaft **9** of Figure 2. The purpose of this joint is to eliminate lost motion between the connected parts, thus contributing to the accuracy of response of the servo-mechanism, and also to allow accidental rotation of the piston shaft without straining the lever system. A block **9a** is fitted over piston shaft **9** (Fig. 4) and is held against conical surfaces **c** by spring **9b**, secured by pin **9d**. Spring **9b** is of such tension as to maintain contact at conical surfaces **c** under all upward loadings encountered in normal operation, but not to load surfaces **c** in excess of this amount; it permits rotation of shaft **9** on block **9a** with a minimum of friction. Trunnion shaft **8** extends from

either side of block 9a and is engaged by V-cut extensions 5a of lever 5. Links 5c connect trunnion shaft 8 to cross pin 5d, which is arranged crosswise of lever 5 in slotted holes 5e. Spring 5b acts between securing pin 5f and cross pin 5d, holding V-cut extensions 5a against trunnion shaft 8 with a force just sufficient to prevent separation under normal loads.

Figure 5 shows details of the joint between pilot lever 12 and flexible rod 17 of Figure 2. The purpose of this joint is to eliminate lost motion between the connected parts, thus contributing to the accuracy of response of the servomechanism. The end of pilot lever 12 is forked and plate 17a on the end of rod 17 fits loosely into this forked part. Pin 15 is pressed tightly through a hole in plate 17a and forms trunnions that rest in V-cuts 12c on fork projections of pilot lever 12. Flat spring 12a is fastened to pilot lever 12 by means of screws 12b. The design of the whole is such that flat spring 12a holds pin 15 against V-cuts 12c of pilot lever 12 with a force sufficient to prevent lost motion under load but not sufficient to cause undue friction in rotation of said pin.

Figures 6, 7, and 8 show details of a special joint employed between shafts 30 and 32 of Figure 2. This device provides in shafts 30 and 32 a hinge joint with a removable pin that is dependably locked in position; said pin is easily removed for disassembly of the shafts, and said pin and locking device are contained within the perimeter of the shaft cross section. In Figures 6, 7, and 8, extension 32a of shaft 32 fits into slot 30a of shaft 30. Pin 31 passes through these two parts and has a hole through its center in which locking pin 31a fits. Locking pin 31a is made of moderately soft metal preformed with one end as shown in Figure 9. As shown in Figures 6 and 7, grooves 30b on the outside of shaft 30 radiate from the center of pin 31, being cut in pin 31 also, and are of a depth slightly greater than the thickness of locking pin 31a. When the joint is assembled, preformed locking pin 31a is placed in position through pin 31 with its bent end fitting in the bottom of groove 30b on one side of shaft 30; the other end is then bent into position in the bottom of the corresponding groove on the opposite side of shaft 30 with pliers or by hammering. When locking pin 31a is preformed to the shape shown in Figure 9, the lengths of the portions on either side of the band are made so that after the pin is installed in the joint, both ends project about half way across grooves 30c, which are cut crosswise of grooves 30b and are a little wider and deeper than grooves 30b in order to accommodate a screw driver or flat tool to facilitate unbending locking pin 31a for disassembly of the joint.

Figure 13 is a kinematic diagram of the servo-lever system, and Figure 14 is a right-angle projection of Figure 13. This system consists of a lever DF, connecting hinge points D, E, and F, which at one limit of its motion is on the line XX; another lever DH which joins lever DF at D at an angle FDH (Fig. 14) and has a fulcrum at G; a bellows device A which is mounted on a shaft joining it to lever DF at E and which causes motion of point E along YY (Fig. 13); a piston B which is mounted on a shaft connecting it to lever DF at F so that motion of point F is restricted to line ZZ parallel to YY. Pilot valve C controls the flow of oil through ports N₁ and N₂ to either side of piston B from inlet O and away from said piston to outlets P₁ and P₂. Pilot valve

C is joined to lever DH at H so that, when said lever rocks on fulcrum G, pilot valve C is caused to slide along line QQ. Any motion of point D that causes such rocking of lever DH will cause sliding action of pilot valve C. Junction D of levers DF and DH may be moved along line XX, as from D₁ to D₂ without causing movement of pilot valve C, inasmuch as point H and motion path G₁G₂ of fulcrum G (Fig. 14) lie in a common plane with line XX at the "neutral" position of pilot valve C.

When the lands M₁ and M₂ on pilot valve C cover ports N₁ and N₂, oil cannot flow to or away from piston B and piston B is thereby locked stationary. (Lands M₃ and M₄ act as seals.) This position of pilot valve C is termed the neutral position. The action of piston B is controlled by bellows A through the linkage described above in the following sequence: Bellows A moves point E to any position E', causing lever DF to assume position D'F and lever DH to assume position D'H'. Pilot valve C is moved upward (Fig. 13) by the amount HH', connecting oil inlet port O to port N₁ and to upper side of piston B and connecting oil outlet port P₂ to port N₂ and to lower side of piston B. Oil pressure then acts downward on piston B causing point F to be moved to F'. Lever DF is thus caused to rock on point E' so that point D' moves upward to point D₁ on line XX at which position pilot valve C is restored to the neutral position, thus arresting motion of piston B as explained above. Bellows motion EE' has thus resulted in piston motion FF'. The magnitudes of these motions are proportional to each other in the ratio D₁E to D₁F inasmuch as triangles D₁EE' and D₁FF' are proportional because lines YY and ZZ are parallel. These proportional triangles will always exist in operation of the control because at equilibrium conditions point D always returns to the same position on line XX. Through this proportional characteristic, a small motion of bellows device A, corresponding to changes in air flow to the engine, may be converted to larger motions of piston B to control the quantity of fuel delivered to said engine with a constant ratio between the magnitudes of said motions.

Adjustment of the motion ratio between bellows A and piston B is obtained by moving point D along line XX as described previously. The ratio of motion FF'/EE' is thus decreased to FF₂/EE' by moving point D from D₁ to D₂ and vice versa.

Figures 15 and 16 show a variation of the system described above. This variation provides a means of reducing the ratio of the piston-bellows motion from the maximum value provided in the dimensions of the system to zero. Such a reduction may be desirable on the subject control to enable the operator to cause the servomechanism to cut off fuel delivery by moving the lever provided for the control of the fuel-air ratio.

In Figures 15 and 16, corresponding points are lettered in a manner similar to Figures 13 and 14. The principal difference in the two systems is that the intersection point D between DF and DH is placed on lever DF between point E, intersection of this lever with the bellows shaft, and point F, intersection of this lever with the piston shaft. The triangles EE'D₁ of bellows motion and FF'D₁ of piston motion, formed by the intersection of the straight lines XX and DF₁, are similar, because EE' and FF₁ are parallel. Point D is always on line XX at equilibrium conditions as in the system of Figure 13, thus, for any posi-

tion of point D on line XX between the limits E and F, these proportional-motion triangles occur. Piston motion in this servosystem is in opposite direction to bellows motion. As point D moves toward F the ratio of piston motion to bellows motion approaches zero, with a corresponding decrease in the setting of the quantity-control lever, so that when points D and F are coincident, the piston locates itself at the lower limit of its stroke regardless of the position of the bellows. This position of the piston causes the quantity-control lever of the fuel-supply apparatus to be set at a minimum or zero fuel delivery. Point D is caused to become coincident with point F by swinging lever DH about center H on axis QQ. (See Fig. 16.) Fulcrum G of lever DH swings on arc G₁G₂ during this motion.

The control system described herein requires that the fuel-injection pump have a speed-delivery characteristic similar to the air-flow-speed characteristic of the engine on which it is to be used. This requirement is necessary in order to account for changes in air flow due to variations in engine speed, inasmuch as such changes in air flow require corresponding changes in fuel flow in order that constant mixture proportions may be maintained. The required speed-delivery characteristic can be obtained by suitable modifications of the fuel-injection pump, lines, and nozzles; that is, if these parts are suitably designed, the variation in fuel flow with speed at a constant setting of the pump capacity-control lever can be made similar to the variation in engine air flow with speed at a given set of the values of the three variables, intake-manifold pressure, intake-manifold temperature, and exhaust back pressure. By the use of a suitable pump speed-delivery characteristic, the control thus takes into account all the variables in the experimentally determined engine-air-flow equation.

The invention described herein may be manufactured and used by or for the Government of the United States of America for governmental purposes without the payment of any royalties thereon or therefor.

Having described our invention, we claim:

1. In a fuel-metering device, the combination of a housing, a hydraulic cylinder and a piston reciprocable therein mounted on said housing, a pilot valve connected to said cylinder for control of fluid flow to either end of said cylinder, a shaft connected to said piston having at one end a connection to the quantity control means of a fuel-supply system, a main lever attached at one end to the other end of said shaft and fulcrumed at midlength to the end of a second shaft attached to means responsive to changes in pressure and temperature of a medium, a second lever attached at one end to said pilot valve and fulcrumed substantially midlength on a stub movable on said housing, said levers swivelled together at their other ends by a joint slidable on either lever, whereby said piston and connection attached thereon is movably responsive to changes in pressure and temperature of said medium, and said pilot valve is centered in neutral position after each piston movement.

2. In a fuel-metering device, the combination of an element responsive to changes in pressure and temperature of a medium, a quantity control element on a fuel-supply system, and means connecting said pressure and temperature responsive element with said quantity control element, said means comprising a hydraulic cylinder, a piston

in said cylinder, a pilot valve for controlling flow of fluid to opposite faces of said piston, a shaft connected to said piston, a lever pivotally attached to one end of said shaft and connected to said pressure and temperature responsive element, a second lever swivelled at one end to said first lever and at the other to said pilot valve, and a movable fulcrum supporting said second lever whereby the effective lengths of said levers may be varied to change the operable setting of said piston and associated quantity control element.

3. In a fuel-metering device, the combination of an element responsive to changes in pressure and temperature of a medium, a control arm of a fuel supply system, and means connecting said element with said control arm comprising a cylinder, a piston reciprocable in said cylinder, a pilot valve for controlling the flow of hydraulic fluid to either face of said piston, a shaft drivably attached to said piston and mechanically connected to said control arm, a lever pivotally engageable with said shaft fulcrumed on said element, a second lever shiftably fulcrumed on a housing enclosing said element and attached to said pilot valve for operation thereof, said levers adjustably connected together at their free ends whereby movement of said element in response to pressure and temperature changes is transmitted to said pilot valve for control of fluid to said piston and said control arm connected thereto, said pilot control adapted to return to neutral at positions of rest.

4. In a fuel-metering device, the combination of an element responsive to changes in pressure and temperature of a medium, a fuel-supply device and means piloted by said element for controlling said fuel-supply device comprising a cylinder, a piston in said cylinder, a pilot valve for controlling the flow of fluid to opposite sides of said piston, a shaft connected to said piston, a lever pivoted at one end to the upper end of said shaft and connected at midlength to said element, a second shaft pivoted intermediate its ends to a movable stub and operatively connected at one end to said pilot valve, said levers being connected to each other at their other ends by a swivelling joint slidable on each lever, said first lever pivoted to said shaft by a lost-motion free joint having a conical surface and matching surface rotatably held together by a spring.

5. In a fuel-metering device, an element responsive to changes in pressure and temperature of combustion air, a fuel-supply device and means piloted by said element for controlling said device comprising a cylinder, a piston in said cylinder, a pilot valve for controlling the flow of fluid to opposite sides of said piston, a shaft connected to said piston, a lever connected at one end to said shaft and pivotally mounted on said element, a second shaft fulcrumed at its midlength to a movable fulcrum and connected at one end to said pilot valve and at the other to said first lever, one end of said shaft operatively connected to a cam which operates a quantity control mechanism of said fuel-supply device, said connection to said cam being a hinge joint having a removable tubular pin with a special lock wire axially securing said pin in said joint, ends of said wire being bent and received in grooves in said pin and shaft of sufficient depth to be contained within the perimeter of said shaft.

6. In a fuel-metering system, a servo motor for translation of movements of a pressure and temperature responsive device comprising a housing, a cylinder with a double-acting piston recipro-
75 cable therein mounted on said housing, a valve for

11

controlling the flow of hydraulic fluid to said cylinder, a pair of levers joined together at their ends by a hinge slidable on each lever, one of said levers fulcrumed on said pressure and temperature responsive device and pivotally connected to said piston, the other of said levers fulcrumed on a stub movably mounted on said housing and connected to said valve, whereby movements of said pressure and temperature responsive device actuate said valve to admit fluid to said cylinder and move said piston a distance proportional to the effective lengths of said levers.
